UNITED STATES PATENT OFFICE.

RICHARD H. ATHEY, OF SAN FRANCISCO, CALIFORNIA, ASSIGNOR OF ONE-THIRD TO JOSEPH CAHEN AND ONE-THIRD TO S. LEVI, BOTH OF SAN FRANCISCO, CALIFORNIA.

FOLDING CAMP HOUSE.

Application filed November 30, 1927. Serial No. 236,702.

This invention relates to portable houses generally and in particular to a foldable camp house.

The objects of the invention are to provide 5 a foldable structure which will occupy but small space when folded and which may be easily set up to form a rigid frame camp house with canvas walls.

Also such a house in which the folding 10 members are provided with locking joints and in which the folding idea is carried out in all members of any great length including the door and the floor beams.

Also such a construction in which a wooden 15 floor is provided and made in sections which cooperate with the foldable floor beams in holding them in position, also such a house in which the assembled floor will be a rigid unit trussed from its corners so that 20 it may be supported on four or more large stones at the corners so as to clear the ground, also such a house in which the super-structure is secured tightly to the rigid floor unit so as to be independent of bracing 25 ropes as used on tents, also such a house in which provision is made for tightly stretching the canvas roof, and also the provision of a canvas ceiling spaced downward 30 from said roof and provision is made for stretching tight said ceiling, and in conjunction with the above features the details of construction by which they are carried out.

In the drawings hereto Fig. 1 is a front 35 elevation of my foldable camp house as it appears when erected with canvas roof and ceiling in place but with the canvas sides omitted so that the frame construction will be clear.

Fig. 2 is a perspective view of the supporting truss frame and floor beams as assembled 40 ready to receive the floor sections and then the house frame.

Fig. 3 is a perspective view of a floor section, a number of which are required to 45 cover the floor beams.

Fig. 4 is a perspective view of one of the truss frame beams partially folded.

Fig. 5 is an enlarged side elevation of one 50 lower corner of the house showing the truss rod and corner connections.

Fig. 6 is an enlarged broken perspective view of one intermediate upright showing the various joining members as just dis-

connected therefrom, and detailing the main 55 folding joints.

Fig. 7 is an enlarged front view of the intermediate upright of Fig. 6 with adjacent members connected thereto and the canvas roof and spaced canvas ceiling in place. 60

In further detail (see Fig. 2) the stiff 65 frame under the floor comprises a plurality of spaced wooden beams 1, herein termed truss beams, and which are each jointed in the center at 2 and stiffened under this joint by short beams 3 slidably secured to the two 70 portions of beams 1 by means of bolts 4 secured to the ends of beams 3 but slidable in slots 5 in the inner or abutting ends of truss beams 1. The arrangement being such that 75 each complete truss beam may be folded to about a third of its length by pulling the ends 1 outward to slide the bolt in the slots and of then turning the beam sections 1 in opposite directions on the bolts as indicated 80 in Fig. 4 until the three beam sections lie substantially parallel. These beams when unfolded to full length are stiff at the joint on account of the inner ends of beam 1 projecting a comparatively long way beyond 85 the bolts 4 and resting against the beam section 3.

Extending at right angles across the truss 90 beams are floor beams 6 each terminating in the center of the central truss beam at 7 and 95 provided with intermediate folding joints 8 hinged at 9.

The two outer floor beams are arranged 100 flush with the ends of the truss beams and are secured to the two end truss beams by through bolts 10 the threaded ends of which project above the floor beams as shown, while between the floor and truss beams at each corner of the house is a truss anchor plate 11 which is apertured to pass the bolt 105 10 and is provided with a hook 12 to which a linked truss rod 13 is anchored as best shown in the detail Fig. 5. These truss rods bear against the under sides of the intermediate truss beams, the center truss beam 100 being provided with blocks as at 14 to make up for the angle involved.

The two folding floor beams at each side, besides being hinged at 9 are stiffened by a short floor beam 15 provided with open metal 105 yokes 16 which engage over the upper and lower surfaces of the sections 6, and the short beam 15 is secured to the truss beam by a

removable bolt 17, or on which bolt it may be swiveled, if desired and kept in place with its particular truss beam when folding the same.

5 The truss floor structure as described and shown assembled in Fig. 2 forms a rigid frame adapted to be supported at its corners only on stones as at 18, or additional stones may be placed under it.

10 The assembled beams of Fig. 2 are next covered with a wooden floor made in uniform sections as shown at 19 in Fig. 3 of a size to rest upon the floor beams and with cleats 20 underneath spaced to come between the 15 floor beams 6 and some suitably notched or spaced to clear the short beams 15 and apertured or notched to clear the corner bolts 10 in the common manner not detailed in the drawings, so that when all the floor sections 20 are laid in place they will form a complete covering for the beams.

At points between the floor beams the floor sections may be additionally supported by blocks 21 placed under the ends of intermediate floor cleats 20' and resting on the truss beams as shown in Figs. 1 and 3.

25 The superstructure comprises corner and any desired number of intermediate uprights as at 22, preferably of square wooden section, 30 secured to the floor by bolts as the corner bolts 10 screwing into the lower ends of the uprights, the uprights being preferably provided with threaded sockets as at 23 to receive the bolts.

35 The upper ends of these uprights are each provided with a pipe fitting T or cross as at 24 pinned in place, and into which the ends of horizontal or plate members 25 and transverse or tie members 26 are removably attached by screwing into the pipe fitting, the square wooden members each having a threaded pipe nipple 27 securely pinned in place.

40 All of the vertical and horizontal pieces 45 are jointed with a tapered splice as at 28 secured by a strap-hinge 29 at both ends of the splice, and the pins of at least one of these hinges of each joint is a loose or removable pin whereby the joint may be folded upon removing the pin, and upon setting up the frame the insertion of the pin or pins forms a rigid lock joint at each place, stiff in all directions.

55 Window openings are provided by any 50 number of spaced vertical sticks as at 30 preferably held in place by short dowels 31 or their equivalents, the sticks being inserted or removed by breaking the joints of the upper horizontal members 26 and lower horizontal members 32 and springing the sticks 30 in or out of place.

60 Lower horizontal members 32 are preferably secured to the uprights by bayonet joints formed by two metal buttons or lugs 33 at the ends of each piece interlocking in

keyhole slots 34 formed in a plate attached to the upright.

The frame is angularly braced in several of the open panels as shown in Fig. 1 wherein an angularly disposed brace rod 35 is hooked at its ends into eyelets 36 screwed into the frame members, and a turnbuckle 37 on the rod provides for tightening it.

An intermediate upright 38 bayonet or dowel jointed to the adjacent structure at 75 its upper and lower ends provides a doorway closed by a door hingedly jointed in its center at 39 and both hinged to the corner upright with loose pin hinges 40. All loose pin hinges used at all points in my house 80 being of the same size so that the pins are interchangeable.

Buttons 41 are provided around the door frame so that screen or solid canvas may be buttoned thereover. Buttons are similarly provided along all frame and window sides for buttoning canvas walls in place and screen material or canvas or both over the window openings.

85 The roof of my structure comprises slanted rafters 42 of square wooden section provided at their upper ends with pipe nipples as previously described and screwed into pipe fittings 43 permanently pinned to a gable piece 44. The gable and rafter members are 90 all splice-jointed with loose pin hinges as described.

95 The rafters are each provided with a block 43 adapted to rest firmly on top of the pipe fitting 24 of the uprights and is 100 secured thereto by a bolt 45 countersunk in the rafter and screwed into a bushing 46 in the fitting (see Fig. 6 wherein the rafter and all adjacent members are shown as partially separated).

105 The roof is covered with a sheet of canvas or other suitable cloth 47 which passes around a longitudinal strip 48 in line with the lower ends of the rafters and thence back under the rafters and is buttoned to the upper edge of the horizontal frame members 25, suitable notches being formed in it where necessary to form a fit around the pipe fittings.

110 Longitudinal members 48 are splice-jointed as described and are for the purpose of tensioning the roof covering being adjustably mounted on rods 49 each pivoted at 50 to the member and slidably supported in a bracket 51 attached to the side of the rafter 120 and provided with a set screw 52 for holding the rod 49 after forcing same and members 48 outwardly to stretch the roof sheet.

115 Spaced below the roof sheet 47 is a sub-ceiling sheet 53 of canvas or the like buttoned along its outer edges to the upper horizontal members of the frame along with the roof sheet 47, and the sub-ceiling sheet passes over a central longitudinal member 54 which may be pulled upward by means of several 125

130

rope slings as at 55 to tension the sub-ceiling sheet to any required degree.

Rope slings 55 secure at their upper ends to an eyelet 56 screwed into member 54 (through an opening formed in sheet 53), thence over a pulley 57 suspended from the gable member, thence downward through the opening in the sheet and through an eyelet 58 screwed into the transverse frame member, the final end being adjustably held at the desired point of adjustment by clip 59.

Ceiling tensioning member 54 is also splice-jointed with loose pin hinges as described, the number of joints used depending on the size of the house, but preferably so arranged that the members after folding will all be within about six feet in length.

Having thus described my improved foldable camp house, I claim:

1. In a camp house a floor comprising spaced beams cross-jointed in the center, a supporting beam below the joint secured to the jointed sections by means of bolts slidably operable in longitudinal slots in the jointed sections.

2. In a camp house a floor comprising spaced beams cross-jointed in the center, a supporting beam below the joint secured to the jointed sections by means of bolts slidably operable in longitudinal slots in the jointed sections and truss rods extending from the outer beams under the intermediate beams.

3. In a camp house a floor comprising spaced beams cross-jointed in the center, a supporting beam below the joint secured to the jointed sections by means of bolts slidably operable in longitudinal slots in the jointed sections, and truss rods extending

from the outer beams under the intermediate beams, floor beams supporting on said spaced beams, and a sectional floor supported on the floor beams.

4. In a foldable house of the character described, slanted roof rafters, a canvas covering over the rafters, a strip at the lower end of the rafters over which the canvas extends, thence returning under the rafters and secured at its end to the house frame, 45 and means positioned between the two rows of canvas arranged and adapted for adjustably forcing said strip outwardly to tension said covering.

5. In a foldable house of the character described, slanted roof rafters, a canvas covering over the rafters, and a ceiling sheet spaced below the roof covering, and means manually operable arranged and adapted 50 for lifting the central portion of the sheet 55 for tensioning the ceiling sheet upwards towards the rafters.

6. In a foldable house of the character described, slanted roof rafters, a canvas covering over the rafters, and a ceiling sheet 60 spaced below the roof covering, and means for tensioning the ceiling sheet upwards 65 towards the rafters comprising a supporting rod under the ceiling sheet and a plurality of rope slings depending from the 70 rafters secured to said rod whereby the rod may be pulled upward by said slings.

7. In a foldable camp house a series of spaced horizontal supporting beams, a superstructure secured thereto by corner bolts 75 passing through said beams, anchor plates on said corner bolts, and truss rods connected to said anchor plates and extending angularly under the intermediate beams.
